FOREIGN PATENT DOCUMENTS

WO89/12020 6/1988 World Int. Prop. O. .

Primary Examiner—Alan P. Douglas*Assistant Examiner*—M. N. Pandozzi*Attorney, Agent, or Firm*—Buchanan Ingersoll**[57]****CLAIM**

The ornamental design for a soda fountain postmix beverage dispenser, as shown and described.

DESCRIPTION

FIG. 1 is a perspective view of my beverage dispenser; FIG. 2 is a front elevational view of my beverage dispenser;

FIG. 3 is a top plan view of my beverage dispenser; FIG. 4 is a right side elevational view of my beverage dispenser;

FIG. 5 is a left side elevational view of my beverage dispenser;

FIG. 6 is a bottom plan view of my beverage dispenser; and,

FIG. 7 is a rear elevational view of my beverage dispenser.

The partial showing of the beverage delivery hose in FIGS. 1, 3, 4, 5, 6 and 7 is shown partially broken away for convenience of illustration.
